IMPROVEMENT IN MACHINES FOR FELTING HAT-BODIES.

JOB W. BLACKHAM, OF BROOKLYN, NEW YORK.

Letters Patent No. 59,758, dated November 20, 1866.

SPECIFICATION.

TO ALL WHOM IT MAY CONCERN:

Be it known that I, JOB W. BLACKHAM, of Brooklyn, in the county of Kings, and State of New York, have invented certain new and useful improvements in Machines for Felting Hats, and I do hereby declare that the following is a full and exact description thereof:

Many efforts have been made to obtain the proper conditions in felting, or as it is technically termed "planking" or "hardening" hats by the aid of machinery.

My machine differs substantially in its construction and mode of operation from all previously known to me. I have felted a sufficient number of hats on it to know that it is practically successful.

My machine contains a bed of rollers, and is adapted to receive the hats thereon at one end of the machine in a rolled-up condition, and to discharge them at the other end in nearly the same condition, except that the material is felted and worked in the interim so as to full and harden the stuff. It is adapted for the direct application of steam and water to the hats during the operation of felting, and can, by increasing the length and number of the rollers, treat a large number of hats at the same time.

I will first describe what I consider the best means of carrying out my invention, and will afterwards designate the points which I believe to be new. The accompanying drawings form a part of this specification.

Fig. 1 is a longitudinal section on the line S S in fig. 2.

Fig. 2 is a plan view with a portion of the upper work removed to show the rolls.

The figures represent but a small number of rolls, but it will be understood that they may be increased in number as required. I believe twenty rolls arranged and operated as represented, each about forty inches long and four or five inches in diameter, to give the best conditions.

Similar letters of reference indicate like parts in both the figures. The tints are employed to aid in distinguishing parts and do not imply material. The material may be of the kinds used in the previous attempts at adapting machinery to this purpose.

A is a rigid frame work, B is a frame adapted to traverse laterally within A.

Rollers having swells thereon, formed and arranged as represented by b b, are supported in the frame B, and are turned continuously all in the same direction and all with equal speed. C is a presser grooved on its under side as indicated by c, and adapted to traverse backward and forward longitudinally of the machine. The hats are treated directly between the bed of slowly revolving rollers B b, and the under surface of the grooved presser C c. A¹ is an inclined board to facilitate the introduction of the previously rolled-up hats. A² is an inclined board adapted to facilitate the delivery of the hats after they have been treated by the machine. The hats are intended to be treated many times in succession, and to be opened and again rolled up at short intervals as is practised in planking by hand.

The machine is actuated by a steam engine or other convenient power, not represented, acting to give a rotary motion to the shaft D, mounted in bearings on the framing A.

Eccentrics d¹ d², fixed on the shaft D by the aid of eccentric straps and rods e¹ e², communicate the proper reciprocating motion to the presser C, by taking hold of the cross-bar C¹, which latter with the corresponding cross-bar C² are fixed across the back of the presser C, and overhang at each end as represented. F F, &c., are slotted levers mounted at the points f, and adapted to guide the presser C in its reciprocations, by taking hold of the cross-bars C¹ C² immediately adjacent to the shoulders c¹ without interfering with any vertical motion to which it may be impelled. G¹ G² G³ G⁴ are springs which may be coiled steel wire as represented, or may be composed of strips of India rubber or analogous material, which are looped over the overhanging ends of the cross-bars C¹ C², and are connected to cords g, or analogous flexible parts passing under pulleys h, and wound around the shafts I I as represented. These shafts I I may be turned by a suitable wrench or other convenient device so as to wind up more or less of the springs G¹, &c., and thus increase or diminish their tension. At each revolution of the shaft D, the presser C c, traverses forward and backward while the springs G¹, &c., described, hold it down upon the hats with more or less force according as the shafts I I are adjusted.

A belt, J, leads over the pulley d³, on the shaft D, and communicates a slower rotary motion to the wheel b¹, which is keyed on a shaft b², carrying a gear wheel b³, which meshes into the first of the train of gearing b⁴ b⁵, and thus imparts a slow rotary motion to the rollers b, all in the same direction as above premised.

The hats are rolled up in the direction indicated by the heavy volute line marked W. At each forward

movement of the presser C, each hat is carried forward by the joint action of the presser and rollers, both tending to move it forward. At each backward movement of the presser each hat remains in the recess between two of the rollers b, simply turning, without moving either forward or backward. The motion of the rollers b tends to carry each forward, but the motion of the presser in the opposite direction tends to work it backward. The speed of the movement of the presser is considerably greater than that of the surfaces of the rollers. This tends to cause a movement of the hat backward; but is not sufficient to actually induce such a movement. The tendency to do so tends to induce a very tight rolling up of the hat, and the hat is thus rolled tighter and tighter as the hat progresses through the machine. I ascribe much importance to this property of my machine. Each forward movement of the presser C, in carrying the hat forward and changing its position, slightly unrolls the hat, but each backward movement of the presser holds the hat in a V-shaped recess and rolls it up again tighter than before.

A connection K, leads from a crank d^4 , on the end of the shaft D, to one arm of the bell crank lever L^1 , which is pivoted at points l^1 , to the framing A. The revolution of the shaft D gives a reciprocating motion to this lever. L^2 is a similar lever pivoted on the point l^2 , and connected by the rod K^1 to the lever L^1 , so as to move in conformity therewith. M^1 M^2 are connections from the other arms of the levers L^1 L^2 , to the carriage B, which supports the rollers b and their connections before described. At each revolution of the shaft D, the crank d^4 and the connected mechanism give a reciprocating motion to the carriage B and its connections; the motion being across the machine in the direction parallel to the axes of the rollers b.

The action induced on the hats by the combination of the longitudinal reciprocating motion of the platform C c, with the continued rotary motion of the rollers b, is sufficiently severe for the treatment of the hat bodies while they are in the soft state in the early stages of the hardening process, and it is therefore desirable that in being treated at that stage each lot of hats be relieved from the cross-motion due to the action of the levers L^1 , L^2 , and their connections. I therefore provide for the disconnection of this latter mechanism and throw it out of use at will.

I effect this by removing the pin d^5 , which is inserted through the crank-pin d^4 , and slipping the connection K off the latter, allowing it to remain idle. The position of this part is indicated in dotted lines in figure 2. In this condition of the machine the hats are felted by the reciprocation of C c, and the rolling of b b, and rolled up and introduced at one end of the machine as they are dropped out at the other end, and opened and re-rolled and again introduced as many times as is required to induce the proper extent of the hardening operation. When they have been hardened to a moderate degree by this mode of treatment I then stop the machine, slip the connection K upon the crank d^4 , insert the pin d^5 , and again start the machine, introducing and removing the hats as before. In this new condition of the machine the hats are more severely treated by the combination of the cross-motion of the rollers b with the several motions before described. It will be observed that the belt J, and its connections, are adapted to impart the proper rotary motion to the several rollers b, in every position of the reciprocating carriage B. After the hats have been treated a sufficient number of times in this more severe manner they will become fully hardened. Toward the close of the operation the workmen may observe the progress at each unrolling and re-rolling of each hat, and may leave out those which are sufficiently hardened until the whole of the lot is completed, and the machine may then be changed back to the simple condition by again removing the connection K from the crank d^4 , and commence on another lot of soft hat bodies.

I do not confine myself to the especial means represented of stopping and again starting the cross-motion of the rollers b. Many well-known mechanical devices may be substituted which will be obvious to good mechanics. The employment of a proper counter-shaft with fast and loose pulleys, or a suitable clutch as a means of stopping and starting the cross-motion, will enable this to be effected without stopping the other parts of the machinery.

If the platform C, and its attachments, be made very heavy, it may be necessary, instead of increasing the load upon itself by the action of the springs G, to relax the force of these springs entirely, and to also relieve the hats of a portion of the weight of the presser and its connections. I can do this by introducing another series of springs acting in the opposite direction mounted parallel to the springs G, or by introducing suspending springs extending down from the ceiling of the apartment or from a suitable framing above, not represented. P represents the lower end of a single spring made adjustable by turning the shaft Q, to which it is connected and adapted to lift on the centre of gravity of the presser as nearly as possible. I have found such to be successful in practice.

I propose in all cases to support a shallow tank of water, N, under the bed of rollers b, and to introduce therein steam pipes having perforations or nozzles n, on their upper sides, and connected to a steam boiler, not represented, so as to throw up jets of steam and water against and between the rollers b, to heat and wet the hats as the work proceeds. The water is applied in a more highly heated condition by these than by any ordinary means, and the direct contact of the steam with the hats I believe to be highly favorable to the object sought.

Having now fully described my invention, what I claim as new and desire to secure by Letters Patent, is as follows:

1. I claim the combination and arrangement of the reciprocating presser C, with the bed of rollers b, so as to treat the hats by the surfaces of the presser and the rollers, substantially as and for the purpose herein set forth.
2. I claim, in connection with the above, so proportioning the extent and velocity of the motion of the presser C, to the size and velocity of rotation of the rollers b, that the hats shall tighten in the roll and tend to stand and roll with only a rotary motion during a great portion of the return movement of the part C, and

shall tend to advance to an extent equal to the diameter of one of the rollers during each forward movement, substantially as and for the purpose herein set forth.

3. I claim, in combination with the presser C, and rollers b, the springs G 1, 2, &c., or their equivalents, arranged as herein specified for increasing the force with which the hat is treated, as and for the purpose herein set forth.

4. I claim, in combination with the presser C, and rollers b, the shaft I, and cords g, or their equivalents arranged as specified for graduating the effect of the force in holding down the presser C, substantially as and for the purpose herein set forth.

5. I claim the spring P, or its equivalent arranged to operate in opposition to the gravity of the presser C, so as to reduce the pressure on the hats, substantially as and for the purpose herein specified.

6. I claim the devices substantially as herein shown and described for putting into and out of action the lateral motion of the bed of rollers b.

JOB W. BLACKHAM.
